CLAIM

The ornamental design for a roof pitch determination tool, as shown and described.

DESCRIPTION

FIG. 1 is a front elevation of the roof pitch determination tool embodying the concepts of my invention; FIG. 2 is a rear elevation thereof;

FIG. 3 is a side view thereof, the side opposite being identical thereto; and,

FIG. 4 is a top plan view thereof, the bottom view being identical thereto.

FIG. 1

FIG. 2

FIG. 3

FIG. 4
